(57) **CLAIM**

The ornamental design for a table/floor lamp, as shown and described.

DESCRIPTION

FIG. 1 is a perspective view of my new lamp design;
FIG. 2 is a bottom view thereof;
FIG. 3 is a front end view thereof;
FIG. 4 is a left side view thereof, the right side view being a mirror image of the left side view;
FIG. 5 is a rear end view thereof;
FIG. 6 is a top view thereof;
FIG. 7 is a perspective view of a modified version of my new design;
FIG. 8 is a bottom view of the design of FIG. 7;
FIG. 9 is a front end view of the design of FIG. 7;
FIG. 10 is a left side view of the design of FIG. 7, the right side view being a mirror image thereof;
FIG. 11 is a rear end view of the design of FIG. 7; and,
FIG. 12 is a top view of the design of FIG. 7.
